UNITED STATES PATENT OFFICE.

EDWARD POSTELL PORCHER, OF COCOA, FLORIDA.

TRUCK.

1,122,801.

Specification of Letters Patent.

Patented Dec. 29, 1914.

Application filed April 20, 1914. Serial No. 333,036.

To all whom it may concern:

Be it known that I, EDWARD POSTELL PORCHER, a citizen of the United States, and a resident of Cocoa, in the county of Brevard and State of Florida, have invented an Improvement in Trucks, of which the following is a specification.

This invention relates to hand trucks for use in moving boxes and packages of various sorts, and more particularly designed for the handling of citrus fruit boxes having panel heads, such as oranges are generally packed in.

One of the principal objects of the invention is to provide a hand truck having gripping arms operable at will by a lever for grasping or releasing a packing box, the arms being so formed as to engage the panel heads of the boxes so as to securely retain the latter on the truck, but without marring or cutting the material of which the boxes are formed, or the labels placed upon the boxes.

A further object of the invention is to provide a hand truck such as described, having a novel and simple arrangement whereby the arms may be operated by a lever to grasp or release the boxes.

Another object of the invention is the provision of a truck of the class described, which will be extremely simple, durable, efficient in operation, and inexpensive to manufacture.

With these and other objects in view which will become apparent as the description proceeds, the invention resides in the construction, combination and arrangement of parts hereinafter more fully described and claimed and illustrated in the accompanying drawings in which like characters of reference indicate like parts throughout the several figures, of which—

Figure 1, represents a front elevational view of the truck, the arms being shown in full lines in releasing position, and in dotted lines in grasping position. Fig. 2, represents a horizontal sectional view taken on the plane indicated by the line 2—2 of Fig. 1. Fig. 3, represents a rear elevational view of the truck, the arms being shown in releasing position. Fig. 4, represents a side elevational view of the truck showing the manner in which the arms are used to grasp packing boxes, and, Fig. 5, represents a fragmentary horizontal sectional view taken on the plane indicated by the line 5—5 of Fig. 4.

Referring more particularly to the drawings, a truck is illustrated at 5, provided with wheels 6, and handles 7, and with foot pieces 8 on the lower ends of the side bars of the truck, said foot pieces being substantially wedge-shaped and tapering from their outer ends toward their inner ends, against which foot pieces the lower edge of the box 65 or article to be moved is adapted to rest.

The front or top edges of the side bars of the truck frame, are recessed as at 9 near the lower ends of the truck, and in the recesses are pivoted by means of bolts passing 70 through the side bars of the truck, or in any other suitable manner, the grasping arms 10 and 11. The arms project laterally from opposite sides of the truck frame, beyond the wheels, and at their outer ends are bent 75 forwardly at right angles, as at 12, and are then off-set inwardly as at 13, the off-set portions of the arms adapted to engage the panel heads of the boxes in the manner indicated in Fig. 4. The arms are preferably 80 made of substantially thin yet strong bars of metal, and it is to be noted that they are free from any obstructions or grasping means, such as teeth or spurs, which if used would not only tend to puncture and tear 85 the boxes and labels, but prevent the insertion of the arms between closely positioned stacks of boxes, it being evident that by reason of the manner in which the arms are formed, they may be inserted without difficulty 90 between closely associated stacks of boxes, thus saving the operator the time and labor which would otherwise be necessitated by the separation of any particular stack from the mass previous to moving the 95 stack. The inner end of arm 10 is offset as at 14, and is curved rearwardly and provided with an elongated arcuate slot 15, through which extends a pin 16 carried near the lower end of a substantially straight hand 100 lever 17, pivoted at its lower end to the rear or under side of the lower cross bar 18 of the truck as at 19, and extending rearwardly substantially the length of the truck and guided by bar 20 supported near the 105 rear end of the truck, said bar being provided with rack teeth 21 to co-act with a tooth 22 carried by the lever in maintaining the latter in any adjusted position throughout the arc of its movement. The 110 rear end 23 of arm 11 is also off-set but to a greater extent than the rear end of arm 10, and is disposed at a slight angle to the arm 11, and extends loosely into a bracket

24 carried upon the rear face of an arm or finger 25, with which lever 17 is provided, and which is disposed to one side of said lever and parallel therewith, and in 5 substantial alinement with the pivot point of arm 10, and pin 16. The arms as shown in full lines in Fig. 1, are in position to grasp a packing box, upon the shifting of lever 17 into the position shown in dotted 10 lines. This operation of the lever will swing arms 10 and 11 rearwardly, in order to bring the off-set portions 13 of the arms into engagement with the box heads, so as to engage under the frames at the ends of the 15 boxes in the manner shown in Fig. 4. The lever having been shifted, may be released and will be held in position by the action of the rack bar, and will be released from this position only when the operator lifts 20 the lever from the bar and moves it in the opposite direction, as will be readily understood.

The device is of such a nature, that it may readily be applied to any trucks now 25 in use, since it requires no special construction of truck for its operation.

It has been found that the operation of the device is extremely efficient and positive, and that rapid, safe and proficient handling of 30 panel head packing boxes has been attained by the use of the truck, and with a minimum amount of labor.

The truck is primarily designed for the purpose of handling panel head shipping 35 cases, but it will be understood that various kinds of boxes and objects may be conveniently moved by the use of the truck, by making slight changes in the shape and construction of the grasping arms, and although the preferred embodiment of the 40 device has been described, I may desire to make such changes in the construction, arrangement and combination of parts thereof as do not depart from the spirit of the invention and the scope of the appended claims.

I claim:

1. A hand truck having its side bars recessed, grasping arms pivoted to the bars within the recesses, and extending laterally 50 on both sides of the truck, and being formed with engaging members at their outer ends, the inner ends of said arms extending toward each other between the said bars, the inner end of one arm being curved rearwardly and provided with an elongated slot, the inner end of the opposite arm being disposed at an angle thereto, a lever pivoted at one end to the truck frame, said lever provided with a pin engaging said slot, and 55 further provided with an off-set arm disposed in parallel relation with the lever, a bracket secured upon said arm into which the angularly disposed inner end of one 60

grasping arm extends, a rack bar for guiding said lever and a tooth carried by the 65 lever adapted to co-act with said rack bar for holding the lever in adjusted position.

2. A hand truck having side bars, grasping arms pivoted to the bars, said arms extending laterally from both sides of the 70 truck and being bent forwardly at right angles, the outer end of said arms being off-set inwardly in parallel relation with the forwardly bent portions and adapted to engage the panel heads of boxes substantially as described, and means for operating 75 the said arms.

3. A device of the class described comprising a pair of bars pivoted intermediate their ends, and extending at one end toward 80 each other, a pivoted lever, a bracket supported by the lever into which the inner end of one of the arms loosely extends, the other arm having its inner end provided with an elongated slot, and a pin carried by said 85 lever and extending through the slot.

4. A hand truck having a pair of arms pivoted intermediate their length thereon, the inner ends of said arms extending toward each other, one of said arms having 90 its inner end curved and provided with a slot, a lever pivotally carried by the truck, a pin carried thereby for engaging the slot, and means carried by said lever for engaging the opposite arm, whereby to move said 95 arms as said lever is moved.

5. A truck, grasping arms pivoted thereon, a lever pivoted thereon and extending longitudinally thereof and movable laterally thereon, a bracket carried by the lever, 100 one of said arms extending at one end loosely into said bracket, and co-acting means between said lever and opposite arm, whereby said arms are moved as said lever is shifted, and means for maintaining said 105 lever in adjusted position.

6. A truck, grasping arms pivoted thereon intermediate their length, said arms extending laterally on both sides of said truck, and at their outer ends being bent forwardly at right angles in parallel relation and off-set inwardly toward each other, the rear ends of said arms being off-set and curved rearwardly in one instance and bent angularly in the other instance, a lever pivoted at one end to said truck, means carried by the lever for engaging the curved and angularly disposed ends respectively to the arms, whereby to move the outer ends of said arms toward and away from each 110 other as said lever is moved, and means for maintaining the lever in adjusted position.

EDWARD POSTELL PORCHER.
